GARTER GRIP

Joseph Jacobs, Bridgeport, Conn., assignor to
 A. J. Donahue Corporation, Milford, Conn., a
 corporation of Connecticut

Application March 28, 1934, Serial No. 717,780

2 Claims. (Cl. 24—245)

This invention relates to garters, and more particularly to a garter grip for detachably connecting the top of a hose to the band encircling the leg of the wearer.

5 One object of this invention is to provide a garter grip consisting of a non-elastic tape which is adapted to be temporarily secured without stitching to the garter button plate and the metal eye loop prior to the attachment of the grip to 10 the garter pad depending from the leg band.

A further object is to provide a garter grip of the above nature in which the tape is provided on one surface with a central line of sticky rubber cement or similar adhesive substance, whereby 15 when the ends of said tape are folded over and pressed upon the body of the tape, the button plate and eye loop will be held securely in assembled position.

20 A further object is to provide a garter grip of the above nature which will be simple in construction, inexpensive to manufacture, easy to manipulate, compact, and very efficient and durable in use.

25 With these and other objects in view there has been illustrated on the accompanying drawing, one form in which the invention may be conveniently embodied in practice.

In the drawing:

30 Fig. 1 represents a perspective fragmentary view of a strip of tape employed in the present invention.

Fig. 2 is a perspective view of the tape as it appears when the garter button plate has been assembled thereto.

35 Fig. 3 is a similar perspective view showing the assembled tape, garter button plate, and garter eye loop.

Fig. 4 is a perspective view similar to Fig. 3, showing the appearance of the garter grip when 40 the tape has been folded over and the eye loop engaged upon the button prior to the final operation of stitching the grip to the depending garter pad.

Fig. 5 is a front elevation of the completed 45 garter, showing the pad stitched to the folded over portion of the tape.

Referring now to the drawing in which like reference numerals denote corresponding parts throughout the several views, the numeral 11 indicates a strip of tape, preferably of non-elastic woven fabric. A narrow line of sticky adhesive material, such as rubber cement indicated by the 50 numeral 12, is applied longitudinally along the center of the tape 11, said line of adhesive ex-

tending the entire length of said tape and being located on one surface only.

In the manufacture of the garter grip, the tape 11 will first be threaded downwardly through both slots of the button plate 13 of a button member 14. The tape 11 will then be looped about the lower edge of the plate 13 and bent upwardly behind the button plate 13 in such a manner that the end of the line of adhesive 12 will lie against the body section of said line, and when the parts are pressed together, the button member will be held securely in assembled position. The parts will then have the appearance illustrated in Fig. 2, and it will be seen that a single thickness 15 of said tape 11 will project above the 10 folded section 16.

A locking eye or loop 17, preferably constructed of wire, will next be assembled upon the upper end of the tape 11 by threading the upper portion 15 of said tape through the lower wide end of the loop 17, and folding the tape 11 downwardly upon itself, as shown in Fig. 3. The contiguous sections of the cement line 12, when 20 pressed together, will serve to maintain the eye 25 loop 17 in the assembled position shown in Fig. 3.

As clearly shown in Fig. 3, the folded over extremities 18 and 18a of the tape 12 are purposely spaced apart so as to leave a small space 19 therebetween.

The upper eye loop 17 and the upper doubled down portion 17a of the tape will next be folded downwardly along the dotted line 19a at the space 19, and the narrow end of the loop 17 will be engaged upon a rubber button 20 upstanding 30 from the body of the button plate 13, as shown in Fig. 4. This completes the assembly of the garter grip, and it will be seen that no basting or 35 stitching operations are necessary as the parts of the garter grip will be held securely in assembled relation without danger of unfolding by the adherence of the folded over sections of the line of rubber cement of the tape 11.

To complete the garter, it will now only be necessary to attach the garter grip to a pad 21 of 45 an elastic leg band 22 by inserting the upper four-thickness fold 17a of the garter grip between the two sections of the lower end of the pad 21. This is accomplished by means of a line of double stitching 24 extending around the edge of the 50 pad 21, as clearly shown in Fig. 5.

While there has been disclosed in this specification one form in which the invention may be embodied it is to be understood that this form is shown for the purpose of illustration only, and 55

that the invention is not to be limited to the specific disclosure but may be modified and embodied in various other forms without departing from its spirit. In short, the invention includes 5 all the modifications and embodiments coming within the scope of the following claims.

Having thus fully described the invention, what is claimed as new and for which it is desired to secure Letters Patent, is:

- 10 1. A garter grip comprising a slotted button plate, an eye loop member, and an elongated tape for connecting said button plate and eye loop member, said tape having one surface coated with a line of sticky adhesive material, said tape having bent-over end loops extending through and embracing said slotted button plate and eye loop members respectively, the surfaces of said bent-over end loops being in intimate adhering con-
- 15

tact with the body of said tape for maintaining said plate and loop member in proper assembled position as a grip unit prior to the permanent attachment of said unit to a garter pad.

2. A garter grip comprising a slotted button plate, an eye loop member, and an elongated tape for connecting said plate and eye loop member, said tape being coated on one side surface with sticky adhesive material and having its ends bent over and extending through openings in said button plate and eye loop member, said bent-over ends being in intimate adhering contact with the body of said tape, the ends of said bent-over tape being slightly spaced apart upon the body of said tape to permit said garter grip to be transversely 10 folded at a single ply prior to the permanent attachment of said grip to a garter pad.

JOSEPH JACOBS.
